UNITED STATES PATENT OFFICE.

ROBERT C. RAHM, OF WYOMISSING BOROUGH, PENNSYLVANIA, ASSIGNOR TO TEXTILE MACHINE WORKS, OF WYOMISSING, PENNSYLVANIA, A CORPORATION OF PENNSYLVANIA.

BRAIDING-MACHINE.

1,153,826.

Specification of Letters Patent. Patented Sept. 14, 1915.

Application filed February 16, 1912. Serial No. 678,014.

To all whom it may concern:

Be it known that I, ROBERT C. RAHM, a citizen of the United States, and a resident of the borough of Wyomissing, in the county 5 of Berks and State of Pennsylvania, have invented certain new and useful Improvements in Braiding-Machines, of which the following is a specification.

This invention relates particularly to 10 braiding machines comprising a connected series of carrier drive gears adapted to operate for plain braiding; and it consists mainly in providing in connection therewith a common-terminal arrangement 15 adapted for stripe braiding and in forming the race-way which determines the movements of the carriers by means of removably secured top-plate sections, as fully described in connection with the accompanying drawings; the novel features of the invention being specifically pointed out in 20 the claims.

Figure 1 is a plan view of a portion of the carrier race-way plate of a braiding machine having my invention applied thereto in preferred form; the carriers from right and left respectively being represented as returning upon the angularly arranged compound terminals which embrace the added 25 common terminal gear. Fig. 2 is a similar view to Fig. 1, but showing the common-terminal course cut out so as to permit the passing through of the carriers as in plain braiding. Figs. 3 and 4 are diagrammatic 30 views indicating modifications of the Fig. 1 construction. Figs. 5, 6, and 7 indicate modified constructions embodying the main 35 features of my invention.

The series of intersecting race-circles 1, 2, 40 3, 4, 5 which are shown in Fig. 2 as forming part of a carrier course for plain braiding, are respectively concentric with a corresponding series of intermeshing carrier drive gears as usual; the only departure 45 shown from the usual arrangement being that the race-circle 3 is located somewhat out of line with the others, and that the top plate 10 of the machine is provided with a removable section 11, adapted to complete 50 the race circles 2, 3, and 4.

Fig. 1 fully illustrates my improved stripe braider construction as applied to the plain braider arrangement of Fig. 2. A carrier drive gear 15, having four carrier 55 engaging horns like the others, but which is

provided with more extended radial grooves, is suitably mounted in toothed engagement with the drive gear of the race circle 3, but separated from the drive gears of race circles 2 and 4; the centers of said gears 15, 2, 60 and 4 being triangularly arranged. The drive gear 15 is adapted to serve as the common member of linked compound-terminals, by coöperating simultaneously with the gear of race-circle 2 and with the gear of 65 race-circle 4 (through the intersecting gear of race-circle 3), so as to return the carriers from the right by passing them through the tangential connecting ways 16 and 17 and the terminal bend 18, while those from the 70 left are similarly passed through the tangential connecting ways 19 and 20 and the terminal bend 21. These ways are formed, as shown, by substituting for the ordinary 75 "quoits" 2^a, 3^a and 4^a, and the removable plate section 11, of the plain braider arrangement shown in Fig. 2, the plate sections 2^b, 3^b, 4^b and 15^b shown in Fig. 1; the effect being to positively guide the returning carriers around the linked compound 80 terminals so as to produce a striped braid instead of passing them through as for plain braiding. The spacing apart of the common-terminal 15 from the coöperating gears of race-circles 2 and 4 respectively, is 85 adapted, as indicated in Fig. 1, to provide in each case a seven-horn compound terminal, with the gear of race-circle 3 serving to transfer the carrier over both the tangential ways 16 and 19. In connection with this 90 common transfer gear are provided additional transfer gears 25 and 26 respectively, 95 triangularly arranged around the common terminal gear 15, thereby providing for moving the carriers over the connecting ways 17 and 20. The looping movements of the two series of carriers as effected for stripe braiding, is indicated in Fig. 1. If it should be desired to use the machine for plain braiding it is only necessary to change 100 the removable plate sections as already described in order to provide for passing the carriers through as shown in Fig. 2. The number of carriers on one or both runs may be varied from that indicated in Fig. 1 by 105 varying the construction, as indicated in Figs. 3 and 4; the compound terminals shown in Fig. 3 being so arranged as to have nine horns each, instead of seven as in Fig. 1; and those of Fig. 4 having seven 110

horns on the right and nine on the left terminal. All of the gears are provided as indicated with the same number of horns, ordinarily four as indicated.

5 In the modifications indicated in Figs. 5, 6, and in Fig. 7, the linked compound terminals are shown arranged in line with the other drive gears and race-circles as usual, instead of being angularly arranged as in 10 the preferred construction of Fig. 1, and the usual series of four transfer gears at 30, 31, 32 and 33 are provided. The outer portion of the race-way for the carriers however, is formed by removably secured plate 15 sections 34, 35, which permit of other race-ways being formed by the substitution of other sections, as shown in Fig. 6 where it will be seen that the carriers are moved around the gears 31 and 32 and thus passed 20 through as required for plain braiding. In Fig. 7 the arrangement is similar excepting that the carriers are passed through on one side only of the main course by providing an additional drive gear 40 and correspond- 25 ingly varying the form of the removable plate sections. Thus in each of the constructions shown the removable plate sections enable the same machine to be used either for plain or stripe braiding.

30 What I claim is:—

1. A braiding machine having a carrier course comprising linked compound terminals, a fixed series of carrier drive gears including supplemental gears adapted to 35 serve either as carrier transfers for said compound terminals or for passing through the carriers, and a carrier race-way formed by removably secured top-plate sections whereby the movement of the carriers is 40 variably determined without changing the carrier driving gears.

2. In a braiding machine having a carrier course comprising a series of three intermeshing drive gears; a common-terminal drive-gear in mesh with the intermediate- 45 one of said three gears; and removable plate sections adapted to form angularly arranged linked-terminal race-ways whereby the movement of the carriers is variably deter- 50 mined without changing the carrier driving gears, substantially as set forth.

3. A braiding machine having linked compound-terminals comprising a carrier drive

gear arranged out-of-alinement with coöperating adjacent gears, and an interposed 55 carrier drive-gear arranged in mesh with said out-of-alinement and adjacent gears and adapted to serve as a common transfer gear substantially as set forth.

4. A braiding machine having linked compound-terminals comprising a carrier drive gear arranged out-of-alinement with coöperating adjacent gears, and an interposed carrier drive-gear arranged in mesh with 65 said out-of-alinement and adjacent gears and adapted to serve as a common transfer gear, all of said gears having the same number of carrier-engaging horns.

5. A braiding machine having linked compound-terminals comprising a carrier drive 70 gear arranged out-of-alinement with coöperating adjacent gears, and an interposed carrier drive-gear arranged in mesh with 75 said out-of-alinement and adjacent gears and adapted to serve as a common transfer gear, and additional transfer gears arranged to coöperate with said common transfer gear substantially as set forth.

6. A braiding machine having linked compound-terminals comprising a carrier drive 80 gear arranged out-of-alinement with coöperating adjacent gears, and three triangularly arranged carrier-transfer gears one of which is adapted to simultaneously serve both compound terminals substantially as 85 set forth.

7. A braiding machine having linked compound-terminals comprising a carrier drive gear arranged out-of-alinement with coöperating adjacent gears, three triangularly arranged carrier-transfer gears one of which is adapted to simultaneously serve both compound terminals and to form part of a through carrier course, and a carrier race-way formed by removably secured top-plate 90 sections whereby the movement of the carriers is variably determined without changing the carrier driving gears, substantially 95 as set forth.

In testimony whereof, I affix my signature, in the presence of two witnesses.

ROBERT C. RAHM.
